US00D829400S

(12) **United States Design Patent** (10) **Patent No.:** **US D829,400 S**
(45) **Date of Patent:** **** Sep. 25, 2018**

(54) **TRASH CAN**

- (71) Applicant: **simplehuman, LLC**, Torrance, CA (US)
- (72) Inventors: **Frank Yang**, Rancho Palos Verdes, CA (US); **Di-Fong Chang**, Torrance, CA (US); **Myk Wayne Lum**, Irvine, CA (US); **Adam C. Wade**, Rancho Santa Margarita, CA (US); **Tzu-Hao Wei**, Hacienda Heights, CA (US)
- (73) Assignee: **simplehuman, LLC**, Torrance, CA (US)

(**) Term: **15 Years**

(21) Appl. No.: **29/608,587**

(22) Filed: **Jun. 22, 2017**

Related U.S. Application Data

- (63) Continuation of application No. 29/548,018, filed on Dec. 9, 2015, now Pat. No. Des. 804,133.
- (51) **LOC (11) Cl.** **09-09**

CLAIM

The ornamental design for a trash can, as shown and described.

DESCRIPTION

FIG. 1 is a top, front, left-side perspective view of a trash can of our design;

FIG. 2 is a top, rear, left-side perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The broken lines shown in the Figures illustrate portions of the trash can that form no part of the claimed design.

1 Claim, 7 Drawing Sheets
